UNITED STATES PATENT OFFICE.

ANNA E. DEWEY, OF AKRON, OHIO.

AUTOMOBILE-JACK.

1,273,833.

Specification of Letters Patent. Patented July 30, 1918.

Application filed November 22, 1917. Serial No. 203,391.

To all whom it may concern:

Be it known that I, ANNA E. DEWEY, a citizen of the United States, residing at Akron, in the county of Summit and State 5 of Ohio, have invented new and useful Improvements in Automobile-Jacks, of which the following is a specification.

This invention has relation to lifting jacks or elevating devices for vehicles, more particularly automobiles. The object of the invention is to provide a jack or elevating device for vehicles which is normally permanently attached to the vehicle and in its inoperative position is drawn up or collapsed 10 close under the vehicle and when in its open or expanded position is capable of raising the entire vehicle bodily from the roadway or other surface on which the wheels of the vehicle usually rest. More particularly the invention embodies two pairs of bars each 15 pair being arranged near one of the two axles of the vehicle and one of the bars of each pair adapted to be raised and lowered simultaneously with the complementary bars 20 of the other pair for lifting or lowering the vehicle thereby equipped. Furthermore, it is contemplated that suitable mechanism 25 will be provided for actuating said movable bars so that they will operate in unison and 30 when they are shifted to their lowered or operative position the vehicle to which they are attached will be raised bodily leaving the wheels free to revolve. It is also an object of this invention to so construct the bars 35 and operating mechanism that when the movable bar is in its inoperative position the same is self contained or inclosed to prevent the accumulation on said mechanism of foreign substances, such as mud, dirt and the 40 like. This is accomplished by making each movable member in the form of a trough and with a permanent fixed complementary trough-shaped member attached to the vehicle and arranged to coöperate with said 45 movable member and inclose or box in the operating mechanism when the movable member is in its inoperative or raised position.

With the foregoing and other objects in view, the invention consists in the novel construction, combination and arrangement

of parts constituting the invention to be hereinafter specifically described and illustrated in the accompanying drawings which form a part hereof wherein is shown the 55 preferred embodiment of the invention, but it is to be understood that changes, variations and modifications can be resorted to which come within the scope of the matter hereinafter claimed. 60

In the drawings in which similar reference numerals indicate like parts in the different figures,

Figure 1 is a transverse cross sectional view of so much of an automobile as will 65 illustrate the connection which this device bears thereto and also showing in connection therewith my improved lifting device in its inoperative or raised position.

Fig. 2 is an enlarged detail view of a 70 threaded shaft employed.

Fig. 3 is a view similar to Fig. 1 showing the device in its open or operative position.

Fig. 4 is a side elevation of the mechanism shown in Fig. 1, illustrating the front portion of a vehicle equipped with this device 75 with the mechanism in its raised or inoperative position.

Fig. 5 is a view similar to Fig. 4 showing the rear portion of the frame of a vehicle 80 with my improved device in its operative position.

Fig. 6 is a longitudinal sectional view of a portion of the operative device, and

Fig. 7 is a perspective view of the operative device in its closed or inoperative position. 85

Referring to the drawings in detail the reference numerals 1 and 2 indicate the side channel irons constituting the frame of an 90 ordinary automobile to which are respectively attached the mud guards 3 and 4, the former being provided with an opening 5, for a purpose to be later described. Attached to the mud guards 3 and 4 are ordinary running boards 6. The device is supported on the usual ground wheels 7. It is contemplated that there will be provided an elevating device or jack near the front axle of the vehicle and a similar one near the rear axle and as these devices are in all respects identical, with slight exceptions which 95

will be described, it is thought that a general description of one will be sufficient for the understanding of them both. Secured to the frame bars 1 and 2 is an inverted trough-shaped member designated generally by the reference numeral 8 and comprising an upper wall 9 and lateral walls 10 and 11. Extending upwardly from the ends of the upper wall 9 are flanges 12 which are secured to the outside of the frame bars 1 and 2 by holding means such as bolts 13. Extending downwardly from the central portion of the upper wall 9 is a lug 14 provided with a semicircular groove in its lower face which is adapted to coöperate with a cap 15 for forming a bearing. At the two ends of the member 8 are downwardly-extending lugs 16 fashioned similarly to the lug 14 and furnishing in connection with caps 17 bearings, the axes of which are in alinement with the axis of the central bearing 14. Mounted in the bearings just described is a shaft 18, shown best in Fig. 2, and comprising a median portion 19 arranged to be received in the bearing in the lug 14, and opposite portions outside of the median portion having reversely-disposed screw threads 20. One end 21 of the shaft 18 is squared to receive an ordinary socket wrench 22 and is positioned in alinement with the opening 5 to permit the insertion of the wrench through the opening to engage the squared end 21 of the shaft 18. The side walls 10 and 11 of the inverted trough member 8 are provided with parallel longitudinally-extending slots 23 for a purpose to be described.

Adapted to coöperate with the member 8 is a movable member denominated generally by the reference numeral 24 and comprising a lower wall 25 and lateral walls 26 and 27. The general contour of the movable member 24 substantially conforms to the outlines both in shape and dimensions with the member 8 and it is contemplated that when the movable member 24 is in its upper position the upper edges of the side walls 26 and 27 will approximately snugly contact with the lower edges of the side walls 10 and 11 of the upper member to thereby form a substantially closed box for containing the mechanism for raising and lowering the member 24. The lower wall 25 of the movable member 24 is provided near the ends thereof with transversely-extending lugs or abutments 28 for a purpose to be later described.

Adapted to travel longitudinally of the member 8 on the threaded portions 20 of the shaft 18 are two nuts 29 and as they are similar a description of one and its connected mechanism is thought to be sufficient. Each nut is approximately T-shaped and with the head portion 30 thereof of suffi-

cient width to engage and be guided in its movement along the threaded shaft by the side walls 10 and 11 of the member 8 arranged to travel in the slots 23. Arranged to be mounted on the trunnions 31 is a link comprising a pair of side arms 32 the ends 70 of which are suitably apertured to receive the trunnions 31 and with the opposite end thereof rounded at 33 and provided with lateral projecting bosses or studs 34. The rounded end 33 of the link is provided with laterally-projecting pins or nogs 35 which are pivotally mounted in suitable apertures in the side walls 26 and 27 of the lower movable member 24, so that the lower member 24 is thereby pivotally connected 80 with said link and the opposite ends of each link pivotally connected with one of the nuts 29. On the ends of the shaft 18 outside of the bearings in the lugs 16 are sprocket wheels 40 and positioned at suitable points on the frame are idler sprocket wheels 41. Extending around the sprocket wheels 40 and held in proper position by the idler sprocket wheels 41 is a sprocket chain 42. The sprocket wheels 40 are fixedly 90 mounted on the shafts 18 and hence when a suitable crank or wrench 22 is applied to the squared end 21 of one of the shafts 18 and rotated the nuts 29 are shifted longitudinally of both shafts 18 due to the engagement of their threaded portions with the threaded portions of said shaft. The movement of these nuts causes the links 32 to rock to lower the member 24 downwardly into the position shown in Fig. 3 and 100 raise the same into its upper position as shown in Fig. 1 depending, of course, upon the direction of movement of the nuts. When the member 24 is in its lower or operative position the lugs 34 on the lower ends 105 of the links 32 engage the transverse lugs or abutments 28 and serve to stiffen the entire structure and prevent lateral movement of the vehicle when raised from contact with the ground or roadway.

I claim,

1. A device of the character described comprising a trough-shaped fixed upper member, a rotatable shaft mounted therein, said shaft provided with two screw threaded portions, the inclinations of the threads of one portion reversely disposed with respect to the threads of the other portion, a nut mounted on each threaded portion, a link pivotally attached to each nut, a movable trough-shaped member pivotally attached to the opposite ends of said links and arranged when said nuts are shifted away from the central portion of said shaft to move said movable member downwardly and when moved in a reverse direction to raise said movable member into coöperation with said first member to form a box-like structure.

2. A device of the character described comprising a trough-shaped member provided with means for attaching it to a vehicle, a rotatable shaft mounted in said member, said shaft provided with two screw threaded portions with the inclinations of the threads of the two portions reversely disposed, a nut mounted on each threaded portion, a link pivotally attached to each 5 nut, a movable trough-shaped member pivotally attached to the opposite ends of said links and arranged to be vertically shifted when said nuts are moved longitudinally of said shaft, said second member when in 10 its upper position adapted to coöperate with the first member to form a box-like structure.
3. A device of the character described comprising a trough-shaped member provided with means for attaching it to a vehicle, a rotatable shaft mounted therein, said shaft provided with two threaded portions with the inclinations of two portions reversely disposed, a nut mounted on each 15 threaded portion, a link provided with two parallel arms pivotally attached to each nut, a movable trough-shaped member pivotally attached to the opposite ends of said links, and arranged to be shifted vertically when 20 said nuts are moved along said shaft, said movable member arranged to coöperate with said first member when in its raised position to form a box-like structure.
4. A device of the character described comprising a trough-shaped upper member having means for securing it to a vehicle, the side walls of said member provided with longitudinally-extending slots, a rotatable shaft mounted in said member, said shaft 25 provided with two threaded portions with the threads of two portions reversely disposed, a nut mounted in each portion, a link attached to each nut, pins projecting laterally from each nut, the pins on each nut arranged to travel in one pair of slots in said member, a movable trough-shaped member pivotally attached to the opposite ends of said links and arranged to be vertically shifted when the position of said nuts is 30 shifted, said movable member arranged when moved to its upper position to coöperate with said first member to form a box-like structure.
5. A device of the character described comprising a fixed trough-shaped member provided with means for attaching it to a vehicle, a movable shaft mounted therein, said shaft provided with two screw threaded portions, the inclinations of the threads 35 of the two being reversely disposed, a nut mounted on each threaded portion, a link pivotally attached to each nut, a lug positioned near the end of each link, a movable trough-shaped member pivotally attached 40 to the opposite ends of said links, an abutment mounted near each end of said movable member and arranged to be engaged by the lugs on said links, said trough-shaped member adapted to be vertically shifted by the movement of said nuts on said shaft and 45 when moved to its upper or inoperative position to coöperate with said first member to form a box-like structure.
6. A device of the character described comprising a pair of trough-shaped members adapted to be arranged in spaced relation and secured to a vehicle, a rotatable shaft mounted in each member, said shafts each provided with two screw threaded portions the inclinations of the threads of the 50 two portions being reversely disposed, a nut mounted on each threaded portion of each shaft, a link pivotally attached to each nut, a movable trough-shaped member pivotally attached to the outer ends of the links attached to each upper fixed member, each of said trough-shaped members adapted to be shifted vertically by the movement of the nuts on each shaft, each movable member arranged when shifted to its upper or inoperative 55 position to coöperate with one of the fixed members to form a box-like structure and means to simultaneously rotate said shafts in unison.
7. A device of the character described comprising a pair of trough-shaped members adapted to be arranged in spaced relation and secured to a vehicle, a rotatable shaft mounted in each member, said shafts each provided with two screw threaded portions the inclinations of the threads of the two portions being reversely disposed, a nut mounted on each threaded portion of each shaft, a link pivotally attached to each nut, a movable trough-shaped member pivotally 60 attached to the outer ends of the links attached to each upper fixed member, each of said movable trough-shaped members adapted to be shifted vertically by the movement of the nuts on each shaft, each movable member arranged when shifted to its upper or inoperative position to coöperate with one of the fixed members to form a box-like structure, and means connecting said shafts for inducing simultaneous rotation of said 65 shafts.
8. A device of the character described comprising a pair of trough-shaped members adapted to be arranged in spaced relation and secured to a vehicle, a rotatable shaft mounted in each member, said shafts each provided with two screw threaded portions the inclinations of the threads of the two portions being reversely disposed, a nut mounted on each threaded portion of each shaft, a link pivotally attached to each nut, a movable trough-shaped member pivotally 70 attached to the outer ends of the links attached to each upper fixed member, each of said movable trough-shaped members adapted to be shifted vertically by the movement of the nuts on each shaft, each movable member arranged when shifted to its upper or inoperative position to coöperate with one of the fixed members to form a box-like structure, and means connecting said shafts for inducing simultaneous rotation of said 75 shafts.

tached to each upper fixed member, each of said movable trough-shaped members adapted to be shifted vertically by the movement of the nuts on each shaft, each movable member arranged when shifted to its upper or inoperative position to coöperate with one of the fixed members to form a box-like structure, sprocket wheels mounted on each

of said shafts, a sprocket chain extending between the sprocket wheels on different 10 shafts whereby simultaneous rotation of the two shafts may be induced.

In testimony whereof I have hereunto set my hand.

ANNA E. DEWEY.
